UNITED STATES PATENT OFFICE.

WILLIAM R. BAKER, OF CHICAGO, ILLINOIS, ASSIGNOR TO THE McCORMICK HARVESTING MACHINE COMPANY, OF SAME PLACE.

GRAIN-BINDER.

SPECIFICATION forming part of Letters Patent No. 283,744, dated August 28, 1883.

Application filed April 27, 1883. (No model.)

To all whom it may concern:

Be it known that I, WILLIAM R. BAKER, of Chicago, in the county of Cook and State of Illinois, have invented certain new and useful 5 Improvements in Grain-Binders, of which the following is a specification.

In a widely-known form of binder, manufactured by the McCormick Harvesting Machine Company for some seasons past, the grain, as it 10 comes over the head of the elevator, is urged forward down an inclined chute or passage by packing-arms, and against compressing or tripping fingers mounted upon or pivoted to the outer end of a supporting-bar, which at the 15 inner end is pivoted to a heel-extension from a vibrating binding-arm, so that the latter in its vibration to encircle the gavel may tend to draw the fingers toward it and subject the bundle to additional compression. An automatic 20 tripping device operated either by the rocking of the compressor-fingers on their pivot as the grain accumulates against them or by other means—as, for instance, an independent trip-lever, such as in a recent improvement 25 made by me—brings the binder-gearing at the proper moment into engagement with a constantly-driven part of the harvester, whereupon a single binding operation ensues. In this movement the binder-arm is vibrated upon 30 its pivot by means of a pitman connecting it with a wrist-pin upon a gear and cam-wheel in the binder-train, and constituting in effect the master-wheel of the binder. The compressing-fingers and supporting-bar are also 35 held in their elevated position to shut off escape of grain from the chute or binding-receptacle until the band has been applied and the knot tied, and to officiate in the ultimate compression above referred to by means of a rock- 40 shaft and link-connection, one of which has usually been made elastically yielding to afford a spring-seat to said supporting-bar, with a T-lever pivoted by one arm to the post-frame of the binder, by another to one of said links, 45 and taking by means of a pin or roller on the third into a cam-track upon the master-wheel, the track having such outline as to retain the supporting-bar in its elevated position until the bound sheaf is to be ejected, then sud- 50 denly lower it to open the chute, and immediately after restore it to position to bring the

compressing-fingers in action for the next binding operation, at which moment the disengagement of harvester and binder takes place.

To guard against accidental dropping or sagging of the supporting-bar and compressing-fingers in the now ensuing interval, until they are again to be intentionally released or dropped for the discharge of the next sheaf, I adopted, some time since, a locking device 55 consisting, essentially, of co-meeting stops or shoulders upon the heel of the binder-arm and the adjacent end of the supporting-bar, whereby when the binder-arm is withdrawn beneath the table it will lock with said bar and tend 60 to hold or thrust it up, preventing it positively from sagging until relieved by the ascent of said arm in the binding action. For this device Letters Patent of the United States No. 242,177 were granted me on the 31st day of 65 May, 1881, and afterward reissued as No. 10,106 on May 9, 1882.

At the foot of the chute, outside of the compressing-fingers, it is customary to place a hinged leaf or tail-board connected by means 75 of a link with the supporting-bar, so that as long as the latter is up in the collecting and binding operation the leaf will be closed as a secondary guard against escape of grain, but when the supporting-bar falls will be thrown 80 down to open the chute.

My present invention introduces the following changes in the organization of the machine thus briefly sketched: In the first place, the cam-track on the master-wheel is dispensed 85 with, as well as all the intermediate mechanism connecting it with the supporting-bar, and said supporting-bar is sustained by toggle-arms connecting it with a bracket from the frame, and themselves rule-jointed, so as to lock when 90 they are in line or slightly past the line with each other, and hold the bar up, but be readily pushed out of line in the other direction to permit the bar to fall. Next, a shouldered 95 push-rod is attached to the heel of the binder-arm to catch upon a pin on one of the toggles and push them out of line as the binder-arm is withdrawn beneath the table, to break their lock and allow the supporting-bar to fall and open the grain-chute, the supporting-bar being 100 immediately raised again by the hereinbefore-mentioned shoulders upon the heel of the

binder-arm and its own contiguous end and the toggles thereby brought back to position, aided, if necessary, by slight spring-pressure in their joint, or external thereto, or by a weight. 5 Finally, instead of connecting the tail-board to the supporting-bar by a link, the end of said supporting-bar is prolonged until it comes beneath the tail-board, and is there furnished with a cam-plate or bracket having a curved 10 cam-track, which engages with a pin or roller on an arm projecting outwardly from the tail-board and operates upon it in such manner that as the supporting-bar falls the tail-board is permitted to open until it reaches a position 15 in line with the decking, or even lower, if desired, and as the supporting-bar rises the board is gradually closed and returned to its original position, where it will be held as long as the bar is up.

20 In the drawings, Figure 1 represents a front end elevation of a binding attachment embodying my invention, and Fig. 2 a detail showing the compressing-fingers and supporting-bar beneath the floor of the grain-chute and the 25 tail-board down.

30 A is the post-frame, B tubular sustaining-bars, and C the flooring or decking of the grain-chute. The packing-arms it is not considered necessary to show; but if employed 35 they will be driven in any suitable—as, for instance, by cranks upon the constantly-rotating shaft D. The loose pinion d upon this shaft, intermittently engaged therewith by the tripping-clutch E, intermeshes with the gear-wheel F, which, by means of an intermediate wheel, 40 F', sets in motion the master-wheel G of the binder. A wrist-pin on this master-wheel connects by a pitman, G', with a crank, g, from the binder-arm shaft and causes the vibrations 45 of the binder-arm H as the wheel rotates.

45 The ordinary tripping-dog, i, actuated by means of a lifter, i', on the end of the rock-shaft I, which bears at its other end the trip-lever i'', is shown by way of illustration as the instrumentation for causing the intermittent action of the tripping-clutch to set the train of gear-wheels in motion. The supporting-bar K is, as heretofore, pivoted to a heel-extension, k, from the binder-arm, and upon this 50 supporting-bar the compressing-fingers K' are either pivoted or rigidly secured, according as they are made to actuate the trip-lever or to serve simply as compressors. Herein their office is supposed to be the former.

55 Upon the heel of the binder-arm is a lug or shoulder, k', and upon the adjacent end of the supporting-bar is a corresponding shoulder or stop, k'', whereby the binder-arm is locked against said supporting-bar and holds it in its 60 elevated position, besides, in the present construction, serving to carry it to said position as it itself descends.

65 A strong bracket, L, offsets from the frame some distance beneath the supporting-bar, and to this bracket is pivoted the lower of two brace or toggle arms, l, the upper one being pivoted to the supporting-bar and the two

working upon a rule-joint, l', which permits them to go slightly inside of the line, each with each, as indicated in Fig. 1 of the drawings, 70 so that while holding the supporting-bar in the elevated position shown they may run no liability of accidental displacement. When, however, the lock between them is broken by any means, they will hinge or fold together, as 75 indicated in Fig. 2, allowing the supporting-bar to recede from the decking and withdraw the compressing-fingers out of the path of the bound sheaf within the chute.

80 The most desirable means for automatically breaking this lock known to me at present is the push-bar M, which I pivot to the heel of the binder-arm somewhat beneath and farther out than the pivot of the supporting-bar. Near its free end, but set a little back therefrom, it 85 has a shoulder, m, which, in the descent of the binder-arm, strikes against a pin, m', on the upper toggle, and pushes both back, so as to break the lock they have formed, and cause them to fold together to open the compressor. 90 The shoulder, as stated, is not at the extreme end of the push-bar, and for this reason, that it is desirable a portion should be left which may rest upon the pin on the toggle-arm while the binder-arm is up, and serve as a guide to 95 bring the shoulder certainly against the pin in the initial descent of said arm.

Immediately after the compressor has been opened it is to be returned to position, the bound sheaf having been discharged in the 100 meantime, and this return takes place during the latter part of the descent of the binder-arm, and is caused, as already stated, by the action of said arm forcing the supporting-bar up. Were the shoulder on the push-bar still 105 in contact with the pin on the toggle at the moment this ascent of the supporting-bar and compressor-fingers is required to commence, the result would be an absolute block or a 110 break of the machinery, since the toggles could not be opened or straightened, and without this the supporting-bar could not be raised. Therefore a shoulder or projection, m'', is 115 formed upon the push-bar beyond or inside of its pivotal attachment to the heel of the binder-arm, which comes against a seat or stop on said heel slightly before the binder-arm interlocks with the supporting-bar, and causes said push-bar to be lifted away from the pin on the toggle or hinged brace in the interval before 120 such lock takes place. Thus at the moment the supporting-bar is to commence its rise the push-bar will be disengaged from the pin, and the action will take place smoothly and easily.

125 The binding-arm alone might not carry the supporting-bar sufficiently high to bring the toggles into line with each other, and in any event could not well, without other mechanism not now shown, cause the toggles to go beyond a precisely straight line, as has been thought 130 advisable. Therefore a spring of not very great strength may be coiled inside the joint, and so attached or seated to the two members of the toggle or brace as to force them past the

line, when they have been brought to or nearly to it; or a pulley and weight may be arranged to draw them into such position. When the binder-arm rises to carry the cord around the 5 gavel and into the knotter or band-securing mechanism, the supporting-bar, relieved from its sustaining contact with said arm, will yet be held up by means of the toggles. The push-bar, however, as the arm ascends, will be 10 gradually lowered until it rests upon and is drawn over the pin on the toggle, bringing its shoulder again inside of that pin. Then, the gavel having been bound and the binder-arm beginning to recede, the push-bar will a sec- 15 ond time break the lock, the supporting-bar will fall, the bound sheaf be ejected, and the supporting-bar immediately thereafter again rise to bring the compressor-arms into position to intercept the incoming stream, and the 20 toggle be reset to hold it in that elevated position.

At the foot of the grain-chute, behind or outside of the compressing-fingers, is pivoted a leaf or tail-board, N. To this tail-board is 25 fastened the arm or casting n, carrying a pin or roller, n', at its point. Upon the end of the supporting-bar, which is suitably prolonged to bring it beneath the tail-board, is fixed the cam-plate or bracket O, having a curved cam- 30 track, o, which engages with the pin or roller on the tail-board casting. The shape of this cam-track is such that when the supporting-bar is up it will have lifted the roller traveling upon it into such position that the tail-board will be closed to intercept straw coming 35 down the chute; but as the supporting-bar falls away from the decking the tail-board will be permitted to gradually descend, its roller coming up the cam-track toward the opposite end from that where it had been previously resting.

In order to make the arrangement more compact, bringing the roll or pin nearer to the tail-board and shortening the supporting-bar, the 45 point of the cam-plate may be allowed to pass through a slot in the lower part of said bar. This will not in any way interfere with its functions; but if there should prove to be any unforeseen objection to it the supporting-bar 50 may be sufficiently lengthened and the roller set so far out from the tail-board as to entirely obviate any necessity for it.

I claim as my invention—

1. The combination, substantially as hereinbefore set forth, of the compressing-fingers, 55 the pivoted supporting-bar, and the hinged brace or toggle.

2. The combination, substantially as hereinbefore set forth, of the compressing-fingers, 60 their pivoted supporting-bar, the brace or toggle having a rule-joint, whereby it locks in extension to sustain the supporting-bar in its elevated position, and means to break the lock and cause the toggle-arms to fold together to 65 depress said supporting-bar.

3. The combination, substantially as hereinbefore set forth, of the compressing-fingers,

their pivoted supporting-bar, the rule-jointed brace or toggle whereby the supporting-bar is sustained, and the push-bar operated by the 70 needle in the descent to force the toggle-arms out of line and cause them to hinge or fold to depress the supporting-bar.

4. The combination, substantially as hereinbefore set forth, of the compressing-fingers, 75 their supporting-bar pivoted to a heel-extension of the binding-arm, the locking shoulders or stops on said bar and arm, whereby the bar is lifted by the binder-arm in its descent, the rule-jointed brace or toggle sustaining said 80 bar, and the push-bar carried by the heel of the binder-arm to break the locked joint of said toggle and cause it to hinge or fold as the binder-arm begins its descent to depress the supporting-bar. 85

5. The combination, substantially as hereinbefore set forth, of the compressing-fingers, their supporting-bar pivoted to the heel extension of the binder-arm, and having a stop 90 against which a shoulder on said heel comes in the continued descent of the binder-arm after the sheaf has been ejected to raise the bar, the rule-jointed brace or toggle which sustains the bar in its elevated position, and the push-bar pivoted also to the heel-extension 95 of the binder-arm, and having a projection or stop which comes against said heel, whereby, as the binder-arm descends, the push-bar is first caused to unlock the toggle to permit the supporting-bar to fall and open the grain-chute after the discharge of the bound sheaf, then the push-bar raised out of the way of the toggle by its contact with the binder-arm in its continued descent, and, finally, the supporting-bar raised into its elevated position 100 105 by the shoulder on its binding-arm, as the latter approaches and reaches its position of rest, and the toggle brought into its effective locking position to sustain said bar.

6. The combination, substantially as hereinbefore set forth, of the grain-chute, the hinged leaf or tail-board, with its projecting bracket and pin or roller, and the cam-plate, 110 with its curved track on the end of the supporting-bar, acting against said pin or roller 115 to open and close the hinged leaf as the supporting-bar falls and rises again to its elevated position.

7. The combination, substantially as hereinbefore set forth, of the compressing-fingers, 120 their pivoted supporting-bar, the cam-plate on the end of the latter having a curved track, the pivoted leaf or tail-board, with its bracket and roller traveling on said track, the rule-jointed brace or toggle sustaining the supporting-bar, and the push-bar for breaking the 125 lock in said brace or toggle and causing it to hinge or fold to depress the supporting-bar, and the binder-arm operating said push-bar and acting to again elevate the sustaining- 130 bar.
